UNITED STATES PATENT OFFICE.

FREDERICK L. FOX AND FRANK C. GIBSON, OF EDGELEA, VIRGINIA.

BASEBALL-GAME APPARATUS.

Application filed July 24, 1919. Serial No. 312,926.

To all whom it may concern:

Be it known that we, FREDERICK L. Fox and FRANK C. GIBSON, citizens of the United States, residing at Edgelea, in the county of Fairfax and State of Virginia, have invented certain new and useful Improvements in Baseball-Game Apparatus, of which the following is a specification.

The object of this our present joint invention is the provision of an entertaining, interest-exciting and skill-exercising apparatus for playing and exemplifying the playing of the modern game of base ball, including all of the fine points and technical phases thereof.

The apparatus is preferably, though not necessarily, for in-door use; the same being susceptible of embodiment, when desired, in a table-like structure that may be conveniently used in a room of ordinary area.

To the attainment of the foregoing the invention consists in the apparatus herein-after described and definitely claimed.

Accompanying and forming part of this specification are drawings illustrative of the best practical embodiment of our invention of which we are cognizant, in which:

Figure 1 is a plan view of the apparatus.

Figure 2 is an enlarged detail section in the plane of the line 2—2 of Figure 1.

Figure 3 is a detail transverse section on line 3—3 of Figure 2.

Figure 4 is a detail plan on an enlarged scale of one of the fielder-figures.

Figure 5 is a section on line 5—5 of Figure 4.

Figure 6 is an enlarged perspective of one of the ball-receivers complementary to the fielder-figures.

Figure 7 is a detail plan of one of the driving connections for manually shifting and positioning the fielder figures, each independently of the others.

Figure 8 is an enlarged detail plan of the diamond portion of the apparatus.

Figure 9 is a detail section on line 9—9 of Figure 8.

Figure 10 is a detail horizontal section showing a portion of the means for moving and controlling the runner figures, the said portion having for one of its functions to retain a runner figure at second base or

third base in the event of a runner figure being sent to first base on four balls.

Figure 11 is a horizontal section taken in a plane below the field-platform.

Figure 12 is an enlarged detail plan of the first-base portion of the field platform.

Figure 13 is a detail plan view of one of the electro-mechanical combinations for operating the switch points.

Figure 14 is a diagrammatic view of the electro-mechanical means for indicating balls and strikes.

Figure 15 is a detail view of one of the three registers or annunciators for "balls", "strikes" and "outs".

Figures 16, 17, 18 and 18^a are views illustrative of the construction of the runner-figures and the elements with which the same cooperate; Figure 18^a being taken in the plane indicated by the line 18^a—18^a of Figure 17.

Figure 19 is a broken vertical section showing a simple form of batting mechanism, according to our invention.

Figure 20 is a similar view of the pitching mechanism.

Figure 21 is a fragmentary broken plan view showing the means for positioning the ball in play relatively to the pitching element in order to bring about the delivery of a ball or a strike as the pitcher desires—i. e., enable the pitcher to guide the ball delivered to the batter.

Figure 22 is a top plan of the electro-mechanical runner-figure control.

Figure 23 is a section taken in the plane indicated by the line 23—23 of Figure 22.

Figure 24 is a detail of the motor-control spring.

Figures 25 and 27 are views of the umpire-figure and appurtenances; Figure 27 being taken on line 27—27 of Figure 25.

Figure 26 is a projected horizontal-section of the umpire control on line 26—26 of Figure 25.

Figure 28 is a detail plan of the run register or annunciator.

Figure 29 is a detail section of the same.

Figure 30 is a diagrammatic view of the circuit system for controlling movements of the umpire-figure arms.

Figure 31 is a view illustrative of a pre-

ferred elaboration of the batting mechanism including means for completing the circuit of the one base-hit control when the ball is struck by the batting mechanism.

5 Figure 32 is a diagrammatic view of the circuit system employed for the operation of the "balls", "strikes" and "outs" registers or annunciators three in number as per diagram and for the resetting of the registers 10 or annunciators when a runner-figure passes a certain point en route to first base on a base hit or when given a base on balls.

15 Figure 33 is a diagrammatic view of the circuit system employed in conjunction with the 1, 2, 3 and 4 base-hit pockets around the out-field portion of the field platform.

20 Figures 34, 35 and 36 are diagrammatic views of circuit systems hereinafter explicitly referred to.

25 Similar numerals and letters of reference designate corresponding parts in all of the views of the drawings.

In the practice of our invention it is proposed to employ nine fielder-figures, Figure 1, 25 the same including a catcher 1, a pitcher 2, and seven infielders and outfielders 3, all in appropriate positions on the field-platform 4 which may be a table top or any other platform compatible with the purposes of 30 our invention. It is also proposed to employ four runner figures 5, one of which is best shown in Figures 16-18^a. The operation of the apparatus also contemplates the employment of an umpire figure U, and the 35 utilization of a ball 6 in play, the said ball being conductive—i. e., a good conductor of electricity. In the preferred use of the apparatus, one group of nine persons will play against a group of corresponding number, 40 and each team will comprise a catcher, pitcher, three basemen, a shortstop, and three outfielders. Nine innings will constitute a game and the game will be carried on in strict accordance with the rules governing 45 the modern field-game of baseball; the teams alternating at the bat and each batting in conformity with a pre-arranged "batting order", and the members of each team, when the same is in the field, being 50 charged with the conduct and manipulation of their respective fielder-figures representing the team. This latter is true of all the fielder-figures except the pitcher and catcher fielder-figures which are stationary and 55 hence not susceptible of manipulation or placing. It is to be understood here, however, that it will be the province of the pitcher of the team in the field to operate the pitching mechanism as will be herein- 60 after set forth in detail. Four runner figures are all that are necessary to represent the "in" team inasmuch as more than four players of an "in" team are never in action or in play at the same time, and the 65 four runner-figures may be used one after

the other to represent the members of a team batting in regular sequence according to the batting order.

Because of the character of the apparatus and for convenience and clearness of description it is regarded as best to separately describe the several portions of the apparatus under different headings, as follows:

The field platform.

The field platform 4 is preferably of the outline shown in Figure 1, and is provided with upstanding side flanges 7, a rear upstanding flange portion 8, and a forward arcuate edge 9, Figures 1 and 2. The flange portion 8 is preferably, though not necessarily, hollow and equipped with one or more transparent panels 8^a. Consequently the said flange portion 8 may, when deemed expedient, be utilized to contain illuminating means. This, however, is not of the essence of our invention and therefore when desired the portion 8 may be a simple confining flange. The arcuate edge 9 is disposed, Figures 1 and 2, in an arcuate series of pockets 10, formed by the outer wall 11, the lower wall 12, the upper overhanging wall 13 and upstanding partition walls 14, with the edge 9 spaced from all of said walls 11-13 in order to enable the ball 6 to drop from the edge 9 to the wall 12. The center of the circle of which the arcuate series of pockets 10 describes a portion is at the "home plate" on the field platform; the foul lines extending from the home plate to the ends of the said arcuate series of pockets as illustrated, Figure 1. Adjacent to said circle are supported eight spaced groups of circuit-closing keys 14^r Figures 1 and 34. 90 At the back of the flange 8 is a group of circuit closing keys 14^s, Figures 1 and 33. Connected to and extending rearwardly from the wall 12, Figure 2, are bars 15, (one to each pocket). Manifestly, a single bar 110 15 may be used if preferred. On each bar 15 are spaced, rearwardly-declined contact bars 16, Figures 2 and 3. Complementary to each pair of contact bars 16 is a rearwardly-declined chute 17, hung at 18, from the platform 4. These several chutes 17 are rearwardly converged in order to enable any one of the same to convey the ball 6 to a rear receptacle 19, carried by the platform 4, from which the ball may be conveniently recovered to be replaced manually in play. On the upper side of the field platform 4 is simulated a diamond 20, with home plate, first, second and third bases and pitcher's box, Figures 1 and 8, and in 125 the platform is formed an opening 21, Figure 9, which extends along the base-running path from one side of the home plate to the opposite side thereof and is bridged by a plate 22 in which is a slot-like opening 23. 130

This slot 23 is provided at one side of the home plate with an arm-like siding 24 which merges into an end enlargement 25, and at the opposite side of the home plate the slot 23 is slightly deflected outwardly and terminates in an end enlargement 26. Adjacent to each base an arm or turn-out 27 diverges from the slot 22, each arm 27 terminating at its outer end in an enlargement 28. Formed in the infield portion of the field-platform 4 are four, preferably arcuate, slots 29, and formed in the "outer garden" portion of said platform are three similar slots 30. Carried on hangers 31, Figures 9 and 16, under the platform 4, is an undulating track 32 which corresponds in configuration to and is vertically aligned with the slot 23, Figure 18. Pivoted at 33, Figure 12, to the platform 4 are switch points 34 for controlling communication between the slot 23 and the turn-outs or arms 27, and fixed to the heel-portions of said points 34 and located below the platform 4 are armatures 35, Figure 13, normally held against stops 36 by retractile springs 37 and complementary to electro-magnets 38, carried at the under side of the platform 4. Also carried at the underside of the platform 4 and arranged adjacent to the second base and the third base are pairs of electro-magnets 39, Figure 10, and complementary to each pair of magnets 39 is an armature plate 40, subject to a spring 41 and equipped with a tappet 42, adapted to be projected into the path of a base-running figure 5, for an important purpose hereinafter set forth.

The means for moving and controlling the runner figures 5.

Passed around three idler sprocket gears 43 and a driving sprocket gear 44 at the underside of the platform 4 is a sprocket belt 45, and on said sprocket belt are four spring-pressed fingers 46 for moving before them the runner-figures 5 after the manner best shown in Figure 10. It will be noticed in this connection, Figures 9-11, that the belt 45 is arranged above and in a plane slightly within the plane of the undulating track 32; also, that when either pair of the electro-magnets 39 is energized, the tappet 42 of said pair will be projected inwardly into the path of the runner figure (see Figure 10) with the result that the runner-figures will be held at second base or at third base, as the case may be; the spring of the finger 46 enabling the outer arm of the finger to swing rearwardly and pass or clear the runner figure 5, after which the spring 41 will return the finger to its normal position in which its inner arm bears against the stop 47. When either pair of electro-magnets 39 is de-energized the tappet 42 thereof will be maintained by spring 41 in the position shown in Figure 10 in which position

said tappet will not interfere with the free passage of the runner figures 5. The driving sprocket gear 44 is fixed upon a vertical shaft 48, Figures 22 and 23, connected through miter gears 49 and 50 with a transverse shaft 51. This shaft 51, in turn, is connected by spur gears 52 and 53 with a parallel shaft 54 on which is a worm gear 55. The said gear 55 is intermeshed with a worm 56 on the armature shaft 57 of an electric motor 58, located under the platform 4. Loose on the shaft 51 are four clutch-members 59, 59^a, 59^b and 59^c, each equipped with a band-pulley 60, Figure 22, and splined on said shaft 51 are two duplex complementary clutch members 61 and 61^a. Circumferential grooves in said members 61, 61^a are engaged by the bifurcated arms of two armature levers 62, 62^a which are yieldingly held in neutral position by springs 63 and each has its outer arm interposed between opposed electro-magnets 64, 64^a, 64^b and 64^c. The band pulleys 60 are connected through four belts 65 with a corresponding number of differential band pulleys 66, 67, 68 and 69. The said pulleys 67-69 are loose on a common shaft 70, and fixed with respect to each pulley is a contact disk; the said disks being lettered A, B, C and D, respectively, Figures 22 and 36. Each of the said disks is provided at one side with a retaining band 80 in which is a gap 81, Figure 24, and for cooperation with the said disks A, B, C, D contact springs a, b, c and d are provided, each spring having a pendent ear e on which is a pin f for engagement within a band 80 and for release through the gap 81 thereof. Disposed above the springs a, b, c and d are electro-magnets a', b', c' and d' the armatures e^a of which are superimposed upon the said springs as shown, Figures 24 and 36. The said armatures e^a are provided with non-magnetic stems e^a, guided in the centers of the magnets. Manifestly when the motor 58 is put in operation, the belt 45 will be driven various distances, (one base, two bases, three bases or home run), according to the pulley 60 that is clutched to the shaft 51, and when the particular traverse of the belt is completed the motor will be caused to stop by the interruption of the supply of current thereto.

The fielder figures.

Each of the fielder-figures 1-3 is provided with a ball-receiver 82, Figure 6, that is preferably of flexible material and is provided in the forward portion of its bottom with an aperture 83 for the gravitation of the conductive ball 6. The catcher fielder figure 1 is also provided with similar ball receivers 82^a, Figures 1 and 8, disposed at opposite sides of its receiver 82. Each of the ball-receivers is attached to a holder 84 that is declined to the surface of plat-

form 4, Figure 5, and carried by each holder 84 are contacts 85, designed to be electrically connected by the interposition therebetween of the ball 6. At this point we would say that our invention contemplates the removal of the ball 6 by a finger of a hand from between any pair of the contacts 85. As before stated the fielder figures 1 and 2 are stationary on the platform 4. The fielder figures 3, however, are susceptible of movement within the limits of their slots 29, Figures 1, 4, 5 and 8. This will be better understood when it is stated that each of the slots 29 is preferably formed in a plate that bridges an opening in the platform 4, and that each of the fielder figures 3 is carried by a pedestal 86, that has a reduced portion movable in one slot 29, and comparatively large portions above and below the slot plate.

In combination with each of the fielder figures 3 we employ a manually-operable equipment such as shown best in Figure 7; the seven equipments being disposed under the platform 4. The said equipments respectively comprise sheaves 87, a drum 88 having a knurled finger piece 89, and a cable 90 connected at its ends to opposite sides of the lower portion of the pedestal 86 and passed about the sheaves 87 and wound upon the drum 88. The seven finger pieces 89 are arranged as shown in Figure 1, relatively to the forward arcuate edge of the field platform 4 and in convenient position to be grasped by those members of the team in the field who play as first baseman, second baseman, third baseman, short-stop, left fielder, right fielder and center fielder, respectively. It is the province of these players to closely watch the batted ball, with their fingers on the pieces 89 and it is also the province of any one of the players, when the ball 6 is batted in the general direction of his particular fielder figure, to manipulate or position such figure as to catch the ball in the receiver 82 thereof. The ball may be received from the platform 4 or caught on the "fly". Likewise it is the province of the outfield players to manipulate their respective fielder figures so as to properly "back up" the infield fielder figures so that in the event of the ball passing one of the infield fielder figures the chance of its being caught in the receiver 82 or the holder 84 of one of the outfield fielder figures will be promoted. The foregoing applies when the ball is batted on the ground and when it is struck into the air and manifestly considerable dexterity will be required to field the ball and prevent it from reaching one of the pockets in the arcuate group at the forward edge of the platform 4. From this it follows that the operation of the apparatus will excite and hold the interest of all the

players and at the same time will exercise their skill; also, that each fielder player is enabled to demonstrate his individual ability as a fielder to a very large extent.

The runner figures.

The runner figures, four in number, will be identical in construction and therefore a detailed description of the runner figure shown in Figures 16-18^a will suffice to impart a definite understanding of all. The said figure comprises a body 90 fixed on a tubular upright 91 of a diameter to freely move in the opening or slot 23 of the diamond. Below the plate 22 the said upright 91 is fixed to and movable with a hollow enlargement 92. Movable rectilinearly in the upright 91 and enlargement 92 is a rod 93 which carries at its lower end a bifurcated enlargement 94 in which is mounted for rotation a travelling wheel 95 that is held in superimposed relation against the undulating track 32 by a spring 96. The upper portion of the upright 91 is longitudinally slotted at 97, Figures 17 and 18, and movable in the slots is a slotted T-head 98 on the rod 93. The said slotted T-head 98 receives pins 99 on leg sections 100, pivoted to the body 90, and consequently when the figure is moved rectilinearly in the slot or opening 23 the rod 93 will be vertically reciprocated, and the upper leg sections 100 and the lower leg sections 101 will be operated in a manner closely simulating the leg movements of a base-running base ball player.

The umpire figure and operating mechanism therefor.

The umpire figure U, Figures 25-27, includes a body and legs arranged in fixed upright position on the platform 4, back of the catcher, Figure 1. Said figure U also comprises arms 103 pivotally connected to the body and adapted to be swung vertically or raised and lowered thereon, singly or in concert. Cranks 104 are fixed to the arms 103, and are connected through pitmen 105 to rods 106 that extend downwardly through upright fixed tubes 107 and are provided at their lower ends with anti-friction wheels 108. Loosely receiving the rods 106 is a cross-head 109, designed to cooperate with abutments 110 on said rods 106 for the simultaneous raising of the latter to raise the arms 103 in concert, and this without interfering with the raising of either arm independently of the other. Fixed to and depending from the center of the cross-head 109 is a rod 112 that extends through a fixed guide 113 and is provided at its lower end with an anti-friction wheel 114. The anti-friction wheels 108 and 114 are superimposed upon the peripheries of three cams 115, 116 and 117. Said cams are mounted

to rotate each independently of the others. The cam 115 is connected through ordinary reduction gearing 115^a with an electric motor 115^b, the cam 117 through ordinary reduction gearing 117^a with an electric motor 117^b, and the cam 116 through spur gears 118^a and 119, a shaft 119^a and reduction gearing 116^a with an electric motor 116^b. On the shaft 119^a is fixed a disk 119^b complementary to cam 116 and in which is a side recess *a*. Each of the cams 115 and 117 is provided in its outer side with a recess lettered *b* and *c*, respectively. At *a'*, *b'* and *c'* are spring-pulled armature latch-levers, and at *a²*, *b²*, and *c²* are electro-magnets complementary to said levers, respectively. The operation of the mechanism just described involves the momentary energization of one of the electro-magnets to release one of the cams, complete the circuit of its complementary motor and bring about the rotation through a complete revolution of its respective cam. Each armature latch-lever, notwithstanding the de-energization of its magnet, will be retained by the side of its cam in position to complete the circuit to its respective motor until its cam makes a complete revolution, whereupon the snapping of the armature latch lever into its respective recess will stop its cam and at the same time interrupt the supply of current to its respective motor. Thus it will be seen that the umpire figure is electro-mechanically controlled in such manner that one arm 103, preferably the right arm, is raised to indicate a "strike", the other arm 103, preferably the left arm, is raised to indicate a "ball", and both arms are raised synchronously to indicate an "out"; also, that following this raising of either arm or both arms and the release of the same, the arm or arms will gravitate to normally pendent positions at the sides of the body of the umpire figure.

The organized pitching mechanism.

By comparison of Figures 1, 8, 20 and 21 the organized pitching mechanism will be readily understood, as comprising a ball positioning member 120 movable in the arc of a circle in the platform 4 at one side of the pitcher Figure 2 and having its upper side flush with the upper side of the platform and also having a slight depression 121, a horizontally-movable lever 122, pivoted at 123 and having an open-frame portion 124 and a finger piece 125 and also having a pointer 126 for cooperation with a graduated scale 127, a ball-impelling member 128, pivoted at 129 to swing in a vertical plane, alongside the pitcher, Figure 2, and having a pad 130 on the face of its head and also having a sector shaped and peripherally grooved lower arm 131, a retracting or setting lever 132, a cable 133 looped about a sheave 134 and effecting connection between

the arm 131 of the impelling member and the lever 132, a spring strip 135 for forcibly moving the impelling member 128 rearwardly, a pivoted and spring-pressed sear 136 arranged to engage a projection 137 on the member 128 and thereby hold the latter against rearward movement, a trigger lever 138, a spring-pressed bell-crank 139 connected through a link 140 with the trigger lever 138 and a cable 141 interposed between and connecting the sear 136 and the bell crank 139 and passed under a sheave 140 and over a sheave 141. The impelling member 128 is movable in a slot 142 in platform 4, and the impact at the completion of its rearward impelling movement is absorbed to a certain extent by a cushion 143. This in combination with the pad 130 lessens noise incident to operation and at the same time lends a degree of elasticity to the blow of the impelling member against the ball with a view to simulating the ordinary delivery of a pitched ball. It will be readily understood from the foregoing that it is the province of the pitcher member of the team in the field to deliver the ball 6 to the batting mechanism; the delivery being effected by first positioning the ball as deemed most expedient through the medium of the member 120 and its appurtenances and after the impelling member 128 is retracted and secured, if desired, in retracted position through the sear 136, and then disengaging the sear 136 by actuation of the key lever 138 to suddenly release the member 128. When the member 128 is so released it will strike the previously positioned ball 6 and drive the same rearwardly toward the batting mechanism, and in this connection it may be stated that when a pitcher player becomes proficient he is enabled by positioning the member 120 precedent to the rearward propulsion of the ball to bring about the hitting of the ball to a particular part of the field. From this it follows that in the working of the apparatus there may be a degree of team work between the pitcher player and the field players which will add materially to the interest and excitement attending the playing of the game. It will also be appreciated that the ball-positioning finger piece 125, the lever 132 and the key lever 138 are positioned in front of the forward portion of the field-platform and hence the batter—i. e., the player who is to manipulate the batting mechanism and who stands behind the field platform 4, cannot see the preliminary movements of the "pitcher" and hence has no way of divining the kind of ball that will be delivered to him. Again the pitcher is enabled to retract the impelling member 128 and then release the same before it is engaged by the sear 126, and consequently either a fast or a slow or a moderately fast ball may be delivered. In other words the pitcher player

is enabled, in the parlance of the game, "to mix" the pitched balls with a view to puzzling and increasing the difficulty of the batter. In this the pitcher player is materially assisted by the adjustable means for tensioning the spring strip 135 so that the member 128 is impelled more or less forcibly. The said adjustable means comprises a slidable support 150 for the spring strip 135 positioned below the latter and movable on a rest 151, and a rod 152 connected to the support 150 and extending forwardly to a point in front of the platform 4 where it terminates in a finger piece 153, Figure 1, so that the support 150 may be adjusted by the pitcher player out of the sight of and without the privity of the batter player—i. e., the player who is for the time being "at the bat" or charged with the operation of the batting mechanism. To further lessen noise incidental to the operation of the pitching mechanism a pad 145 is provided at the rear end of the slot 146 in which the lever 132 is movable.

25 The organized batting mechanism.

The organized batting mechanism of our invention, Figures 1, 8, 19 and 31, comprises a batting member movable in a longitudinal vertical slot in the platform 4 in front of the catcher figure 1 and a sear 155 for holding the batting member in its retracted position. The batting member may be of the simple type shown in Figure 19 or of the more elaborate and preferred construction disclosed in Figure 31. For the sake of convenience, however, we will first describe the construction shown in Figure 19. According to this construction a slot 156 with a cushioning pad 157 at its forward end is provided, and the batting member 158 is mounted to swing in said slot and be detachably secured in its retracted position by its complementary sear 155. The batting member 158 is designed to be impelled forwardly by the spring strip 159 and to be retracted against the action of the said strip until it is engaged by the sear 155, through the medium of the lever 160 and a cable 161, the cable being connected to the lower sector-shaped arm of the member 158 and passed around a sheave 162, and the lever being movable in a slot 163 in the rear portion of the platform 4 and out of the sight of the pitcher player. At its forward end the slot 163 is preferably provided with a pad 164 to lessen noise during operation. The sear 155 is disengaged to release the batting member through the medium of the key-lever 165, Figures 1 and 10, located at the rear of platform 4 and out of the sight of the pitching player, a spring-pulled bell-crank 166 connected with said lever, and a cable 167, passed over a sheave 168 and connecting the sear and said bell-crank. At

169 is a circuit maker and breaker that is closed when the batting member is retracted and open when said member is impelled forwardly, and at 170 is a circuit maker and breaker that is open when the batting member is retracted and closed when the said member is impelled forwardly. In the preferred form shown in Figure 31 provision is made for completing the circuit of the "one base hit" control when the ball is struck, and for preventing closure of said circuit when the ball is missed by the batter, the batting member 158^a being equipped with a ball-striking lever plate 171, pivoted at 172 and having its lower arm adapted to bring up against a buffer 173 on a pendent bracket 174 at the underside of the platform 4. The upper arm of the striker plate 171 normally rests as shown relatively to the batting member unless said arm brings up against the ball, the lower arm of the striker plate engaging the buffer 173, and preventing back-lash of the upper arm. When, however, the upper arm of the plate 171 strikes the ball, said arm will be forced rearwardly. This will have the effect of forcing rearwardly a bolt-like contact member 175, and the said member will be secured in retracted position by a latch 176, so as to enable the member 175 in cooperation with a complementary contact member 177 on member 158^a to close the electric circuit alluded to. The said member 175—177 will remain in contact until the head of the member 175 abuts against the stationary anvil 178 when the member 175 will be released from the hold of the latch 176 and the circuit will be opened by the movement of member 175 away from member 177. As indicated by the dotted and arrow-pointed lines in Figure 19, the batting member 158 or 158^a is adapted to bat a "liner" or fly balls describing various arcs of circles and is also adapted to drive the ball on a line or into the air toward center field, left field or right field according to the line on which the ball approaches the batting member and the position of the batting member when it engages the ball.

26 The run registering or announcing mechanism.

Figures 28 and 29 show the run registering mechanism as comprising a revoluble disk 180 bearing a circular series of figures in regular sequence, say from 0 to 8, adapted to be displayed through a sight-opening (not illustrated). Fixed to and revoluble with the disk 180 is a pulley 181 that is connected through a belt 182 with a pulley 183 on a wheel 184, located horizontally at one side of the portion of the slot-like opening 23 in the plate 22 that approaches the home plate. The wheel 184 is provided with a plurality of radially-disposed sockets 185 in

which are rectilinearly-movable fingers 186, each thrust outwardly by a spring 187 and each provided with a collar flange 188. When the wheel 184 is at rest, one of the fingers 186 intersects or extends transversely across the vertical plane of the said portion of the slot-like opening 23 and with its collar flange 188 arranged as best shown in Figure 29 relatively to an upstanding curvilinear flange 189 on one arm of a spring-pulled armature lever 190, the other arm of which is adapted to bring up against a stop 191 and is opposed to an electro-magnet 192. In Figure 28 a runner figure is shown as approaching and about to engage one of the fingers 186 as the runner figure approaches the home plate to score a run, and it will be readily understood that by acting against the presented finger 186, the runner figure will turn the disk 180 one space to score the run. At the end of each inning reference may be had to the disk 180 for the convenient ascertainment of the runs scored in said inning.

25 *The registers or annunciators for balls, strikes and outs.*

These registers, (three in number) are shown in Figure 32, and Figure 15 illustrates in detail the balls register. This register comprises a swinging sector-disk 193 bearing figures say from 0 to 4 adapted to be displayed through a sight opening (not shown), and is equipped with an abutment 194. Fixed with respect to the disk 193 is a ratchet 195, and revolute independently of both disk 193 and ratchet 195 is a toothed disk 196 on which is an arm 197 to engage the abutment 194 and which is designed to 40 be moved in the direction indicated by arrow by a convolute spring 198 which is put under tension by turning of the disk 196 in the direction opposite to that indicated. The disks 193 and 196 are turned step by step reversely to the arrow through a part of a circle and are then released to permit restoration movement of said disk 193 by the spring 198 and disk 196 in the direction of the arrow and back to initial position. The 45 means for effecting the first-named movement of the disks 193 and 196 and the subsequent release of said disks includes an armature 199 backed by a spring 200 and opposed to an electro-magnet 201, a spring-pulled armature lever 202 opposed to an electro-magnet 203 and equipped with a detent 204 and an arm 205 on which is a cross-head 206, and a spring-backed detent finger 207, pivoted to the armature 199 and slotted 50 to receive the arm 205 in such relation as to enable the cross-head 206 on said arm to pull the detent 207 out of engagement with the ratchet 195. Each energization of the magnet 201 will manifestly bring about the turning of the disk 193 reversely to the arrow the

distance of one space or notch, the teeth of disk 196 riding past the detent 204 which holds disk 196 against movement in the direction of the arrow. When the magnet 203 is energized to disengage the detent 204 from disk 196, and the detent 207 from ratchet 195, the spring 198 will return the disks 196 and 193 to the position shown.

At 208 is a normally-open circuit-closing device, arranged to be closed by the arm 197 on disk 196.

The "balls," "strike" and "outs" registers shown diagrammatically in Figure 32 are similar in construction, and the "balls" disk 196 is also shown diagrammatically in Figure 35 as provided with an additional radial arm 197^a which may also serve, if desired, as one of the ratchet teeth.

At this point we would have it distinctly understood that it is within the purview of our invention to arrange the registers or annunciators either upon or below the field platform or at any point or points more or less remote from the field platform.

25 *The electro-mechanical umpire and control means.*

Comparison of Figures 6, 8, 25, 26, 27 and 30 will make clear the electro-mechanical umpire control means when it is stated that the reception of the conductive ball in the central receiver 82 of the catcher figure 1 and the electrical connection of the contacts 85 in said receiver will be attended by momentary energization of the electro-magnet b² to enable the armature lever b' to close at c⁸ the normally-open circuit c⁹ including a source of electrical energy c¹⁰ and the motor 115^b whereupon the motor will be actuated to raise the left arm of the umpire figure to indicate a strike, and then when the armature lever b' is enabled to again enter the recess in its complementary cam 117 the circuit alluded to will be interrupted at c⁸. Reception of the conductive ball in one of the receivers 82^a of catcher figure 1 and the electrical connection of the contacts 85 in receiver 82^a will cause momentary energization of the electro-magnet c² to enable the armature lever c' to close at b⁸ the normally-open circuit b⁹ including the source of energy c¹⁰ and the motor 117^b whereupon said motor will be actuated to raise the right arm of the umpire figure to indicate a ball, and then when the armature lever c' is enabled to again seat in the recess in its cam 115 the last mentioned circuit will be interrupted at b⁸. Closure of the circuit including the magnet a² and a source of electrical energy will be attended by energization of said magnet a² to enable the armature lever a' to close at c⁸ the normally-open circuit a⁹ including the source of energy c¹⁰ and the motor 116^b whereupon the motor will be actuated to synchronously raise both arms of the umpire figure to 13

indicate an out, and then when the armature lever a' is enabled to again enter the recess in its complementary disk 119^b, Figure 26, the circuit alluded to will be interrupted at 5 a^s . We deem it necessary here to state that the normally open circuit including the "out" magnet a^s also includes circuit-closing means hereinafter explicitly set forth.

- 10 *The electro-mechanical means for operating the registers or annunciators and resetting the same after the "batter up" has hit the ball.*

Under this heading particular reference 15 will be had to Figures 6, 8, 14, 15, 19, 30 and 32.

It is to be assumed that a pitched ball is delivered and lands in the receiver 82 of the catcher figure 1, when the conductive ball 20 will electrically connect the contacts 85, denominated "strike" in Figure 32. If the conductive ball lands in either of the receivers 82^a of said catcher figure it will connect the contacts 85 thereof, both pairs of 25 such contacts being denominated "Balls" in Figure 32. In the first case the ball will register one strike through the medium of the "strikes" register, Figure 32, the current taking the course indicated by solid arrows, 30 Figure 32, from one pole of the indicated source of electrical energy through the electrical connections, including magnet 201^c and the conductive ball 6 shown by dotted lines, back to the opposite pole of the source 35 of electric energy. In the second case the ball will register one ball through the medium of the "balls" register shown diagrammatically in Figure 32 and in detail in Figure 15, the current taking the course indicated by dotted arrows, Figure 32, from one 40 pole of the said indicated source of electrical energy through the electrical connections, including the magnet 201^c and the conductive ball 66^c, shown by dotted lines, back 45 to the opposite pole of the source of electric energy. It will be noticed here that the "balls" circuit is through the circuit closer 169, and the circuit closer 170 is shown in Figure 32 as open. From this it follows that 50 in the event of the batter having struck at the ball 6^c received in either of the "balls" receivers 82^a, a ball will not be registered. On the other hand the "balls" circuit will be interrupted at 169, Figures 19 and 32, 55 and the "strikes" circuit will be completed at 170 so that the magnet 201^c will be energized and the "strike" register will be actuated. Under the circumstances just stated, the course of the current from one pole of 60 the indicated source will be by wire i , wire j , circuit closer 170, wire k , magnet 201^c, and wire l back to the opposite pole of the source. The opening of the circuit closer 169 and the closing of the circuit closer 170, as when 65 the batter offers at but misses a ball which

is received in the catcher's receiver 82, will manifestly, for the reasons just stated, not interfere with the energization of the magnet 201^c and the registering of a strike by the "strike" register. The magnets 203 of the "balls", "strike" and "outs" registers are connected, Figure 32, through the wire l with one side of the source of electric energy, and through a wire m with a terminal n located adjacent to the path of the runner figures at a point between the home plate and first base. It will also be understood from said figure (32) that a terminal p is electrically connected with the sprocket belt 45 and that a wire r electrically connects said terminal p with the before mentioned wire i . By virtue of these provisions it will be understood that a runner figure 5 in passing to first base will energize the "balls" and "strikes" magnets 203 and reset the registers 85 complementary thereto. Thus if a man is at the bat and makes a hit after the charging of say three balls and two strikes against him, the runner-figure 5 will, in passing to first base, reset the "balls" and "strike" registers. This will be better understood when it is stated that when the runner figure contacts with the terminal n , a circuit will be completed through the three magnets 203, the course of the current being from one side 95 of the source of energy through the wire l , the magnets 203, the wire m , terminal n , runner-figure 5, sprocket belt 45, terminal p and wires r and i back to the opposite side of the source of energy. When desired in 100 incandescent lamps 204, Figures 14 and 32, may be arranged in parallel with the magnets 201 and 201^c to visually indicate balls and strikes; the said lamps being, by preference, differently colored and arranged in 105 the casing 8, Figure 1, or at any other desired point or points in the discretion of the party making use of our invention. Figure 32 also illustrates the electro-magnets 38 and magnet 192 for controlling the switch points 110 34, Figures 11, 12 and 13, complementary to the first base, second base, third base and "home" turnouts of the slot 23, Figure 8; the said magnets being appropriately designated in Figure 32. It will be observed in 115 said figure that these magnets 38 are arranged by wires 340 and 341 in normally open circuits with the magnet 201^c of the "outs" register so that one of the magnets 38 will be energized immediately precedent 120 to each energization of the magnet 201^c. An incandescent lamp 204 is also, by preference, arranged in parallel with the magnet 201^c as shown.

In the operation of the means shown in 125 Figures 28 and 29, each runner-figure 5 as it passes the wheel 184 on its way to the home plate will turn the wheel 184 one point and thereby register a run. This obtains provided the runner-figure is not "out at home". 130

In the event that the runner-figure is out at home, the fielder will close a circuit including the magnet 192 by pressing his key 14^r bearing the inscription "Out at home", and in consequence the magnet 192 will be energized. This energization will be attended by the drawing to magnet 192 of one arm of the armature lever 190 and will result in the other and flanged arm of said armature lever 10 retracting the presented finger 186 so that the runner figure in passing will not register a run.

In Figure 35 we show the electro-mechanical means including the "balls" register, Figure 15, slightly modified, for controlling runner-figures 5 at the bases. On one of its disks, preferably the disk 196, the register has two arms or projections 197, 197^e for cooperation with circuit closers 208 and 209, 15 complementary to the "one base hit control" and the second and third base control means, respectively. The utility of these provisions will be appreciated when it is stated that assuming the batter represented by runner-figure 5 has been given his base "on balls", the projections 197, 197^e will have closed the circuit-closers 208, 209 and the figure 5 will be moved by movement of the sprocket belt 45 to first base. At the same time current 20 will pass from one side of the indicated source of electrical energy along the course indicated by arrows to the belt 45 and from said belt by way of the terminal p' and the wire r' back to the other side of the source 25 of energy. From this it will be understood that if under the condition stated there is a runner-figure 5 on second base and a runner-figure 5 on third base, said runner-figures 5 will be held at second and third bases, respectively, notwithstanding the movement 30 of the runner-figure (given its base on balls) with the belt 45 to first base. This is due to the energization of the magnets 39 and the detention of the runner-figures 5 at second 35 and third bases by the mechanism shown in Figure 10 without interfering with the movement of the belt 45. In the event, however, of there being a runner-figure 5 on first base and a runner-figure 5 on second base when the runner-figure 5 at the bat is given its base "on balls", the runner-figure 5 at first-base will interrupt the described circuit by holding open the circuit-closer 500 sufficiently long to enable the runner-figure 5 at second base to pass the tappet 42, Figure 10, adjacent to second base, and the runner figure 5 that was at first base to pass to second base; the pairs of magnets 39 being of course de-energized at that time. because of the interruption in the circuit, and all three runner-figures mentioned being moved with the belt 45 by the fingers 46 thereon. The circuit-closer 500 serves, of course, to close the indicated circuit when 65 the runner-figure 5 located at first base at

the time and under the condition stated is moved to second base.

Reference will now be particularly had to Figures 22, 23, 24, 31 and 36; the latter figure illustrating the circuit system for the 70 operation and control of the motor 58 and its complementary clutches etc. As before described, the upper arm of the lever-plate 171 will not move rearwardly to press the contact member 175 into engagement with 75 the member 177 unless said upper arm is forced rearwardly by the impact of the pitched conductive ball 6, of steel or other appropriate material. When, however, the upper arm of the lever plate 171 is forced 80 rearwardly by the mechanical engagement thereof with the ball 6, the "one base hit" circuit, Figure 36, will be closed by the engagement of member 175 with member 177. Assuming that the hit made is a "three-base 85 hit" and the ball 6 is received between the contact members of a three-base-hit receiver at the forward end of the field platform, as shown by heavy dotted lines in Figure 36, the circuit will first be completed at 175-177 90 and the magnet d' complementary to the disk A will be energized, the current taking the course of the solid arrows in Figure 36 from one side of the indicated source of energy back to the other side thereof. This operation attends the making of every hit—i. e., every impact of the pitched ball 6 against the upper arm of the lever-plate 171. The energization of the particular magnet d' alluded to will complete the circuit between the elements A and 80, Figure 23, said 95 circuit being through the motor and the magnet 64 of the clutch complementary to disk A so that the said disk A will be driven through one complete revolution, whereupon the element f will be raised through gap 81 and out of engagement with element 80. Now with the assumption stated, the conductive ball 6 rests between and electrically connects the contact members in the "three-base 100 hit" receiver, Figure 36, and completes the circuit at such point with the result that the magnet M, Figure 36, will be energized and will attract its complementary armature N and engage the same with its spring latch 115 P so that the circuit will be completed at Q. This circuit, however, is interrupted at R until the disk A has made the complete revolution referred to which revolution will have the effect of moving the runner-figure 5 120 through the medium of the belt 45 to first base. With the runner-figure 5 at first base the element a complementary to disk A assumes the position shown in Figure 23, and in consequence current will pass through and 125 energize the magnet c' complementary to the disk C and depress the element c opposed thereto for the completion of the circuit through the magnet 64^e, Figures 22 and 36, and rotate disk C through one complete 130

revolution and thereby bring about the movement of the runner-figure 5 to second base and to third base in succession, consonant with the degree of the hit made, as 5 stated. It will be noticed in this connection that by the arrangement shown, the disk A will be caused to make one revolution for a one-base hit; also, that a two-base hit will bring about one revolution of the disk A 10 and one revolution of the disk B, while accompanying a three-base hit the disk A will be turned through one revolution and the disk C through one revolution. In the event of a four-base hit or "home run", 15 the disk A will be turned through one complete revolution, and the disk D also through one complete revolution. In fact the revolutions of the three disks B, C, D, 20 are controlled by the element *a* complementary to the disk A at the point R in Figure 36.

From the foregoing it is thought that the operations incidental to the making of base hits of different degrees will be readily understood when it is stated that a one base hit 25 will be attended by the turning of the disk A through one revolution, a two base hit will be attended by the turning of the disks A and B each through one revolution in succession, a three base hit will be attended by 30 the turning of the disks A and C each through one revolution in succession, a four base hit or home run will be attended by the turning of the disks A and D each through 35 one revolution in succession. In this connection it will be observed that the ratio of the pulley 67 of disk C to its complementary clutch pulley is two to one, and the ratio of the pulley 66 of disk D to its complementary 40 clutch pulley is three to one, so that the effect of the revolution of the disk C will be to move a runner-figure the distance of two bases, and the effect of the revolution of the disk D will be to move a runner-figure the 45 distance of three bases.

It being remembered that the players representing the fielder-figures are grouped about the forward arcuate end of the field-platform, it will be seen by reference to Figure 34 that we make provision whereby a fielder whose respective fielder-figure catches the ball can control the runner-figure associated with the batting of the ball, and this without interference from any other 50 fielder. This latter will be better understood when it is stated that the conductive ball 6 is the controlling factor and that, therefore, no fielder can control the runner-figure unless the ball 6 effects electrical connection 55 between the contact members of the fielder-figure representative of such fielder. Thus the fielder whose fielder-figure catches the ball can put the runner-figure out at first base, at second base, at third base or at the "home 60 plate," as opportunity offers and the judgment

ment of the fielder dictates. It will be noticed that each fielder has under his control a plurality of four circuit closing keys 14^r, carried upon the field-platform as shown in Figure 1 and illustrated diagrammatically in Figure 34, and hence each fielder is enabled to control—i. e., put out, a runner figure 5 at first base, at second base, at third base and at the home plate. Therefore assuming that the fielder-figure representing the party "playing" center field catches the ball and a circuit is completed by the ball in cooperation with the contact members of the center fielder figure, as indicated by the heavy dotted lines, the center fielder alone 75 can control the runner figure. Thus with the batter runner-figure 5 moving toward first base and the runner-figure 5 that was on first base moving toward second base, the center fielder, because of the length of the hit, would have for his play to put out the batter-runner figure at first base. Consequently the said center fielder would press the 1st base key 14^r of his group of keys so as to energize the first base magnet 38 and divert the runner figure into the turnout 27 at first base, indicating that such runner figure is "out at first." The runner figure may then be readily lifted through the enlargement 28 at the outer end of the turnout and in that way moved from the field-platform. It will be understood from this that any one of the fielders can, as occasion offers, put out a runner figure at any one of the bases or at the "homeplate"; also, that the arrangement is such that double plays and triple plays by a fielder are possible, and many opportunities are offered for testing the quickness and the baseball "generalship" of each fielder as well as enabling a fielder, in the 100 parlance of the game, "to pull a bone," all of which features manifestly contribute materially to the interest and amusement afforded by the use of the apparatus. The contact member at one side of the home plate and the 105 brush at the opposite side of the home plate in Figure 34 render it possible to operate the one base hit control magnet shown at the right of the diamond when there are no runner figures on the bases and the runner figure at the bat is the only one to be dealt with.

We illustrate in Figure 33 a modified circuit system slightly different from that shown in Figure 36; for controlling the motor 58. It will be noticed in said figure 33 that the contact members of all of the fielder-figures are connected with the one base-hit control so that when the ball is received between a pair of contact members 16 and a 115 circuit is thereby completed, the runner-figure will be caused to move or "run" from the home plate to first base. While desirable, this arrangement in our judgment is not 120 as attractive from the standpoint of interest 125 130

as the system shown in Figures 36 and 31 wherein, as explicitly described, the lever-plate 171 on the bat will complete the one-base hit circuit when it strikes the ball, 5 whereupon the batter will start toward first-base, thereby closely simulating the best practice in modern base-ball as scientifically played. It will be noticed here that in the arrangement shown in Figure 33, the disk 10 A' will be turned through one revolution for a one-base hit, the disk B' through two revolutions for a two-base hit, the disk C' through three revolutions for a three-base hit, and the disk D' through four revolutions 15 for a four base hit or home run; also, that in the arrangement of Figure 33, we dispense with the magnets M, armatures N, spring catches P and circuit control R of Figure 36.

At 14° in Figure 33 we show the circuit-20 closing keys to shunt the runner figures into the turnouts of the slot in the field platform with a view to facilitating the removal of the runner figures from the diamond.

It will be apparent from the foregoing 25 that the apparatus of our present joint invention is well adapted to play and exemplify the playing of the modern game of baseball in a scientific manner closely simulating the actual playing of a game by two 30 teams, and that because of the character of our apparatus it is designed especially for use in clubs and like places where two teams of nine players each are readily available.

Having described our joint invention, 35 what we claim and desire to secure by Letters Patent, is:—

1. In a game apparatus, the combination of a platform having an opening therein following the base running lines of a base-40 ball diamond and also having a base siding opening leading from the first opening, a runner-figure movable in said first opening and into said siding opening, and means for switching the said figure from the first 45 opening into said siding opening.

2. A game apparatus comprising a plat-50 form characterized by an opening formed therein along the base running lines of a base-ball diamond and having an outer field base siding opening leading from the first opening, and means for switching a figure traversing said first opening into said siding opening.

3. In a game apparatus, the combination 55 of a platform having an opening therein following the base running lines of a base-ball diamond and also having a base siding opening leading from the first opening, a runner-figure movable in said opening, and 60 electro-mechanical means for switching said figure from said opening into said siding opening.

4. A game apparatus comprising a plat-65 form characterized by an opening formed therein along the base running lines of a

base-ball diamond and having an outer field base siding, and electro-mechanical means for switching a figure traversing said opening, from the opening into said siding.

5. In a game apparatus, the combination 70 of a platform having an opening therein following the base running lines of a base-ball diamond and also having base-sidings, a runner figure movable in said opening, and means for switching the said figure 75 from the opening into any one of the adjacent sidings.

6. In a game apparatus, the combination 80 of a platform having an opening therein following the base running lines of a base-ball diamond and also having outer field base-sidings adjacent to the outer corners of the opening, a runner figure movable in said opening, and means for switching the said figure from the opening into any one 85 of the said sidings, said means being electro-mechanical.

7. A game apparatus comprising a plat-90 form characterized by an opening formed therein along the base running lines of a base-ball diamond and having outer field base-siding openings, a figure movable in the first opening and from said openings into any one of the outer field siding openings, means for moving said figure, and 95 means for switching the figure from the first opening into any one of the siding openings.

8. A game apparatus comprising a plat-100 form characterized by an opening formed therein along the base running lines of a base-ball diamond and having outer field base-sidings, a figure movable in the first opening and from the same into any one of the side openings and means for switching the figure traversing said opening, from the opening into any one of said sidings, the said means being electro-mechanical.

9. A game apparatus comprising a plat-110 form characterized by an opening formed therein along the base running lines of a base-ball diamond and having sidings, one adjacent to each base of said diamond, and switch-points for diverting a figure traversing said opening from the opening into 115 any one of said sidings.

10. A game apparatus comprising a plat-120 form characterized by an opening formed therein along the base running lines of a base-ball diamond and having sidings, one adjacent to each base of said diamond, and switch-points for diverting a figure traversing said opening from the opening into any one of said sidings combined with electro-mechanical means for controlling said 125 switch points.

11. A game apparatus comprising a plat-130 form characterized by an opening formed therein along the base running lines of a base-ball diamond, and also having sidings

from said opening at points adjacent to the bases, in combination with means for moving a figure in said opening along said lines, and means for switching the figure into any one of said sidings.

12. A game apparatus comprising a platform characterized by an opening formed therein along the base running lines of a base-ball diamond, and also having sidings 10 from said opening at points adjacent to the bases, in combination with means for moving a figure in said opening along said lines, means for switching the figure into any one of said sidings, and means for disengaging the figure from the moving means 15 to cause said figure to dwell at second base or at third base.

13. A game apparatus comprising a platform characterized by an opening formed 20 therein along the base running lines of a base-ball diamond, in combination with electro-mechanical means for moving a figure in said opening along said lines, and means for disengaging the figure from the 25 moving means to cause said figure to dwell at a base.

14. In a base ball game apparatus, a platform having arcuate pocket means bordering an outfield space, a conductive ball movable 30 on the platform and into said pocket means at different points in the length of the latter, said platform also having means complementary to said pocket means for enabling the conductive ball received in the 35 pocket means to close an electrical circuit.

15. In a base ball game apparatus, a platform having arcuate pocket means bordering an outfield space, a conductive ball movable 40 on the platform and into said pocket means at different points in the length of the latter, said platform also having means complementary to said pocket means for enabling the conductive ball received in the 45 pocket means to close an electrical circuit, and means for conveying the ball from said bordering pocket means to the rear portion of the platform.

16. In a game apparatus, a platform having an arcuate series of side-by-side pockets 50 bordering an outfield space, a conductive ball movable over the platform and into said pockets, normally open electrical circuits associated with the pockets, said platform also having means complementary to each pocket 55 for enabling the conductive ball received in any pocket to close the electrical circuit associated with the pocket.

17. In a game apparatus, a platform having a plurality of side-by-side pockets bordering a field space, a conductive ball movable 60 over the platform and into said pockets, said platform also having means complementary to each pocket for enabling the conductive ball received in any pocket to 65 close an electrical circuit associated with the

pocket, in combination with a receptacle carried at the rear portion of the platform, and rearwardly declined and converging chutes leading to said receptacle.

18. In a game apparatus, a platform having a plurality of side-by-side pockets bordering a field space, a conductive ball movable over the platform and into said pockets, said platform also having means complementary to each pocket for enabling the 70 conductive ball received in any pocket to close an electrical circuit associated with the pocket, in combination with a receptacle carried at the rear portion of the platform, and rearwardly declined and converging chutes 75 leading to said receptacle, said chutes being formed in part by said circuit-closing means.

19. In a game apparatus, a platform having an opening following the lines of a 80 base-ball diamond, a conductive ball movable on the platform, said platform also having pocket means bordering a field space and means complementary to said pocket means for enabling the conductive ball received in the pocket means to close an electrical circuit, in combination with means for moving a runner-figure along said opening.

20. A game apparatus comprising a platform having a base-ball diamond, in combination with electro-mechanical means for moving a figure along the base-running lines of said diamond, and electro-mechanical means for causing the figure to dwell at a 90 base.

21. A game apparatus comprising a platform having a base-ball diamond, in combination with electro-mechanical means for moving a figure along the base-running lines of said diamond, and electro-mechanical means to disengage the figure from the moving means and to cause the figure to dwell at a base notwithstanding continued movement of the moving means.

22. In a game apparatus, a platform having an opening following the lines of a base-ball diamond and also having pocket means bordering a field space and means complementary to said pocket means for enabling the conductive ball received in the pocket 110 means to close an electrical circuit, in combination with means for moving a runner figure along said opening, and electro-mechanical means to disengage the figure from the moving means and to cause the figure to dwell at second base or at third base 115 notwithstanding movement of the moving means.

23. The combination in an apparatus for playing the game of base-ball, of means to 125 actuate player figures, an umpire figure connected with and actuatable by said means, and strikes, balls and outs registers connected with and actuatable by said means.

24. A game apparatus comprising a plat- 130

- form, a fielder figure having ball-receiving means and spaced contact members in said means and a conductive ball for cooperating with said contact members to complete a normally open electrical circuit including the contact members and circuit controlled means.
25. A game apparatus comprising a platform, a fielder-figure movable thereon and provided with means for fielding a ball and also with spaced contact members included in a normally open electrical circuit with circuit-controlled means, and means to manually move the said figure.
- 15 26. An apparatus for playing and exemplifying the playing of the modern game of base-ball, comprising a field platform equipped with contact members, fielder-figures equipped with contact members, a conductive ball, a runner-figure, electro-mechanical means for moving the runner-figure different distances along the base-running lines of a base-ball diamond and controlled by electrical circuits including the first-named contact members, and electro-mechanical means for diverting a runner-figure from the base running lines at bases to put the runner-figure out and controlled by electrical circuits including the second-named contact members.
- 20 27. An apparatus for playing and exemplifying the playing of the modern game of base-ball, comprising a field platform equipped with contact members, fielder-figures equipped with contact members, a conductive ball, a runner-figure, electro-mechanical means for moving the runner-figure different distances along the base-running lines of a base-ball diamond and controlled by electrical circuits including the first-named contact members, and electro-mechanical means for diverting a runner-figure from the base running lines at bases to put the runner-figure out and controlled by electrical circuits including the second-named contact members, in combination with electro-mechanical means for detaining a runner-figure at second base or at third base without interfering with the movement of the moving means as when a runner figure is given its base on balls and is moved from the home plate to first base.
- 25 28. An apparatus for playing and exemplifying the playing of the modern game of base-ball, comprising a field platform equipped with contact members, a conductive ball, a runner figure, and electro-mechanical means for moving the runner figure different distances along the base running lines of a base-ball diamond and controlled by electrical circuits including said contact members and adapted to be closed by said ball.
- 30 29. An apparatus for playing and exemplifying the playing of the modern game of base-ball, comprising a field platform, fielder figures equipped with contact members, a conductive ball, a runner figure, means for moving the runner figure along the base running lines of a base-ball dia-
- mond, and electro-mechanical means for diverting a runner figure from the base running lines at bases and controlled by electrical circuits including said contact members.
- 35 30. An apparatus for playing and exemplifying the playing of the modern game of base-ball, comprising a field platform, fielder figures equipped with contact members, a conductive ball, a runner figure, means for moving the runner figure along the base running lines of a base-ball diamond, and electro-mechanical means for diverting a runner figure from the base running lines at bases and controlled by electrical circuits including said contact members, and also including manually actuatable circuit closers.
- 35 31. An apparatus for playing and exemplifying the playing of the modern game of base-ball, comprising a field platform equipped with contact members, fielder-figures equipped with contact members, a conductive ball, a runner-figure, electro-mechanical means for moving the runner-figure different distances along the base-running lines of a base-ball diamond and controlled by electrical circuits including the first-named contact members, and electro-mechanical means for diverting a runner-figure from the base running lines at bases to put the runner-figure out and controlled by electrical circuits including the second-named contact members, in combination with electro-mechanical means for detaining a runner-figure at second base or at third base without interfering with the movement of the moving means as when a runner figure is given its base on balls and is moved from the home plate to first base.
- 40 32. An apparatus for playing and exemplifying the playing of the modern game of base-ball, comprising a field platform, a runner figure, means for moving the runner figure along the base-running lines of a base-ball diamond, and electro-mechanical means for detaining a runner figure at second base or at third base without interfering with the movement of the moving means as when a runner figure is given its base on balls and is moved from the home plate to first base.
- 45 33. An apparatus for playing and exemplifying the playing of the modern game of base-ball, comprising a field platform, a runner figure, means for moving a runner figure along the base-running lines of a base-ball diamond, and electro-mechanical means including manual circuit closers to divert a runner figure from the base running lines at bases to put the runner out.
- 50 34. An apparatus for playing and exemplifying the playing of the modern game of base-ball, comprising a field platform, a runner figure, means for moving a runner

figure along the base-running lines of a baseball diamond, and electro-mechanical means including spaced contact members, a conductive ball, and manual circuit closers to 5 divert a runner figure from the base running lines at bases to put the runner out.

35. An apparatus for playing and exemplifying the playing of the modern game of base-ball comprising a field platform 10 equipped with contact members, a conductive ball, a runner figure, a batting mechanism including a circuit maker and breaker mechanically closed by the action of the ball against the bat, and electro-mechanical 15 means for moving the runner figure different distances along the base running lines of a base-ball diamond and controlled by electrical circuits including said contact members and the circuit making and breaking 20 means of the batting mechanism.

36. An apparatus for playing and exemplifying the playing of the modern game of base-ball, comprising a field platform equipped with contact members, fielder figures equipped with contact members, a conductive ball, a runner figure, a batting mechanism including a circuit maker and breaker operable to close a circuit by the mechanical action of the ball against the 30 bat, electro-mechanical means for moving the runner figure different distances along the base-running lines of a base-ball diamond and controlled by electrical circuits including the first-named contact members and 35 the circuit maker and breaker, electro-mechanical means for diverting a runner-figure from the base running lines at bases to put the runner figure out and controlled by electrical circuits including the second named 40 contact members and also including manually-actuable circuit-closers, and electro-mechanical means for detaining a runner figure at second base or at third base without interfering with the movement of the 45 moving means as when a runner figure is given its base on balls and is moved from the home plate to first base.

37. An apparatus for playing and exemplifying the playing of the modern game of base-ball, comprising a field platform equipped with contact members, fielder figures equipped with contact members, a conductive ball, a runner figure, a batting mechanism including a circuit maker and breaker operable to close a circuit by the mechanical action of the ball against the bat, electro-mechanical means for moving the runner figure different distances along the base-running lines of a base-ball 55 diamond and controlled by electrical circuits including the first-named contact members and the circuit maker and breaker, electro-mechanical means for diverting a runner-figure from the base running lines at bases 60 to put the runner figure out and controlled

by electrical circuits including the second named contact members and also including manually-actuable circuit closers, and electro-mechanical means for detaining a runner figure at second base or at third base without interfering with the movement of the moving means as when a runner figure is given its base on balls and is moved from the home plate to first base, in combination with an umpire figure having movable arms, and electro-mechanical means for moving the arms of said figure consonant with the happenings of the game. 70

38. An apparatus for playing and exemplifying the playing of the modern game of base-ball, comprising a field platform equipped with contact members, fielder figures equipped with contact members, a conductive ball, a runner figure, a batting mechanism including a circuit maker and breaker operable to close a circuit by the mechanical action of the ball against the bat, electro-mechanical means for moving the runner figure different distances along the base-running lines of a base-ball diamond and controlled by electrical circuits including the first-named contact members and the circuit maker and breaker, electro-mechanical means for diverting a runner-figure from the base running lines at bases 80 to put the runner figure out and controlled by electrical circuits including the second named contact members and also including manually-actuable circuit-closers, and electro-mechanical means for detaining a runner figure at second base or at third base without interfering with the movement of the moving means as when a runner figure is given its base on balls and is moved from the home plate to first base, in combination with strikes, balls and out registers, and electro-mechanical means for actuating said registers consonant with the happenings of the game. 90

39. In an apparatus for playing and exemplifying the playing of the modern game of base-ball, comprising a field platform equipped with contact members, fielder figures equipped with contact members, a conductive ball, a runner figure, a batting mechanism including a circuit maker and breaker operable to close a circuit by the mechanical action of the ball against the bat, electro-mechanical means for moving the runner figure different distances along the base-running lines of a base-ball diamond and controlled by electrical circuits including the first-named contact members and the circuit maker and breaker, electro-mechanical means for diverting a runner-figure from the base running lines at bases 100 to put the runner figure out and controlled by electrical circuits including the second named contact members and also including manually-actuable circuit-closers, and electro-mechanical means for detaining a runner figure at second base or at third base without interfering with the movement of the moving means as when a runner figure is given its base on balls and is moved from the home plate to first base, in combination with strikes, balls and out registers, and electro-mechanical means for actuating said registers consonant with the happenings of the game. 110

130

electro-mechanical means for detaining a runner figure at second base or at third base without interfering with the movement of the moving means as when a runner figure 5 is given its base on balls and is moved from the home plate to first base, in combination with an umpire figure having movable arms, electro-mechanical means for moving the arms of said figure consonant with the happenings in the game, strikes, balls and out 10 registers, and electro-mechanical means for actuating said registers consonant with the happenings of the game.

40. An apparatus for playing and exemplifying the playing of the modern game 15 of base-ball, comprising a field platform equipped with contact members, fielder figures equipped with contact members, a conductive ball, a runner figure, electro-mechanical means for moving the runner figure different distances along the base running lines of a base-ball diamond and controlled by electrical circuits including the first-named contact members, electro-mechanical 20 means for diverting a runner figure from the base running lines at bases and controlled by electrical circuits including the second-named contact members and also including manually-actuatable circuit closers, 25 electro-mechanical means for detaining a runner figure at second base or at third base without interfering with the movement of the moving means as when a runner-figure is given its base on balls and is moved from home plate to first base, an umpire figure having movable arms, and electro-mechanical means for moving the arms of said figure consonant with the happenings in the game, strikes, balls and outs registers, 30 and electro-mechanical means for actuating said registers consonant with the happenings in the game.

41. An apparatus for playing and exemplifying the playing of the modern game 35 of base-ball, comprising a field platform equipped with contact members, fielder figures equipped with contact members, a conductive ball, a runner figure, electro-mechanical means for moving the runner figure different distances along the base running lines of a base-ball diamond and controlled by electrical circuits including the first-named contact members, electro-mechanical 40 means for diverting a runner figure from the base running lines at bases and controlled by electrical circuits including the second-named contact members and also including manually-actuatable circuit closers, 45 electro-mechanical means for detaining a runner figure at second base or at third base without interfering with the movement of the moving means as when a runner-figure is given its base on balls and is moved from home plate to first base, an umpire figure having movable arms, and electro-mechanical means for moving the arms of said figure consonant with the happenings in the game.

42. An apparatus for playing and exemplifying the playing of the modern game 50 of base-ball, comprising a field platform equipped with contact members, fielder figures equipped with contact members, a conductive ball, a runner figure, electro-mechanical means for moving the runner figure different distances along the base running lines of a base-ball diamond and controlled by electrical circuits including the first-named contact members, electro-mechanical 55 means for diverting a runner figure from the base running lines at bases and controlled by electrical circuits including the second-named contact members and also including manually-actuatable circuit closers, 60 electro-mechanical means for detaining a runner figure at second base or at third base without interfering with the movement of the moving means as when a runner-figure is given its base on balls and is moved from home plate to first base, strikes, balls and outs registers, and electro-mechanical means for actuating said registers consonant with the happenings in the game.

43. An apparatus for playing and ex-

emplifying the playing of the modern game of base-ball, comprising a field platform equipped with contact members, fielder figures equipped with contact members, a conductive ball, a runner figure, electro-mechanical means for moving the runner figure different distances along the base running lines of a base-ball diamond and controlled by electrical circuits including the first-named contact members, electro-mechanical means for diverting a runner figure from the base running lines at bases and controlled by electrical circuits including the second-named contact members and also including manually-actuatable circuit closers, 70 electro-mechanical means for detaining a runner figure at second-base or at third base without interfering with the movement of the moving means as when a runner figure is given its base on balls and is moved from home plate to first base, an umpire figure having movable arms, electro-mechanical means for moving the arms of said figure consonant with the happenings in the game, strikes, balls and outs registers, 75 and electro-mechanical means for actuating said registers consonant with the happenings in the game.

43. The combination with an apparatus 80 for playing the game of base-ball including a player figure and means to actuate the same, of an umpire figure connected with and actuatable by said means.

44. The combination with an apparatus 85 for playing the game of base-ball including means to actuate a figure, of strikes, balls and outs registers connected with and actuatable by said means.

45. An apparatus for playing base-ball comprising a platform, manually-movable 90 means for positioning a ball, a spring-actuated impelling member movable against the placed ball, means for retracting said member, and means for releasing the same; the ball-positioning means being movable transversely of the line of movement of the impelling member.

46. An apparatus for playing base-ball comprising a platform, manually-movable 95 means for positioning a ball, a spring-actuated impelling member movable against the placed ball, means for retracting said member, and means for releasing the same; the spring-actuating means of the impelling member being manually adjustable to tension the same; the ball-positioning means being movable transversely of the line of movement of the impelling member.

47. An apparatus for playing base-ball comprising a platform, a batting member, 100 and circuit-closing means controlled by movement of said batting member.

48. An apparatus for playing base-ball comprising a platform, a batting member carrying contact members one of which is 105

movable relatively to the other, a latch complementary to said movable contact member, a lever plate carried by the batting member and also complementary to said movable contact member and adapted to receive the impact of a ball engaged by the batting member, and an anvil for releasing the movable contact member from its latch and moving it away from the complementary contact member.

49. In an apparatus for playing the game of base-ball, the combination of a platform, a runner figure, electro-mechanical means for moving said figure, a conductive ball, contact members for cooperation with said ball, electro-mechanical means for controlling the movements of the moving means consonant with the happenings in the game, the electro-mechanical means for moving said figure being controlled by electrical circuits including said contact members.

50. In an apparatus for playing the game of base-ball, the combination of a platform having a slot and turnouts at the bases in communication therewith, a sprocket belt movable below the platform, electro-mechanical means for moving said belt, a runner figure movable in the slot and by the belt, and electro-mechanically actuatable switch points under control of players for diverting a runner figure from the slot into the turnouts.

51. In an apparatus for playing the game of base-ball, the combination of a platform having a slot following the base running lines of a diamond, a belt movable below the platform and carrying spring-pressed fingers, a runner figure movable in the slot before said fingers, and electro-mechanical means controlled by the happenings in the game for detaining a runner figure at second base or at third base.

52. In an apparatus for playing the game of base-ball, the combination of a platform having a slot following the base running lines of a diamond, a belt below the platform, an undulating track below the platform, and a runner figure movable in the slot and by the belt and having movable limbs and also having means connected with said limbs and arranged to travel on the undulating track to actuate the limbs incidental to movement of the figure in the slot.

53. An apparatus for playing baseball, comprising a platform having a first base, means for moving a runner-figure on the platform, balls and strikes registering means, and means actuatable by the movement of a runner figure to first base on "a base on balls" to reset said registering means.

54. An apparatus for playing baseball, comprising a platform, runner figures, means for moving the latter, and electrically controlled means for detaining a runner figure at a base or runner figures at

bases when another figure is moved to first base on "a base on balls," said electrically controlled means being subject to the movement of the last-named figure.

55. The combination with apparatus for playing base ball including a platform, a runner figure, means for moving the runner figure, and manually controlled fielding means, of run-registering means operable by a runner figure, and means controlled by the fielding means for preventing the registration of a run as when a runner figure is put out at "home."

56. In ball game apparatus, the combination of a platform, electro-mechanical means for moving a runner figure, and batting means including electro-mechanical means to put into operation the electro-mechanical figure moving means and effect the movement of a runner figure from "home" to first base when the batting means is engaged by a ball.

57. A ball game apparatus, comprising a platform, runner-figure moving means, batting means, and electro-mechanical means to put in operation the means for moving the runner-figure moving means and to control the extent of such operation to effect movements of the figure different distances according to the varying lengths of hits.

58. A ball game apparatus comprising a platform, batting mechanism, ball registering means including a receiver, strike registering means including a receiver, a ball to cooperate with said ball registering means and with said strike registering means, and means for actuating the strike registering means on operation of the batting mechanism even though the ball is deposited in the receiver of the ball-registering means.

59. A ball game apparatus comprising a platform, a ball, means to move runner figures, means to bat or impel the ball, electro-mechanical means to move the runner figure moving means different distances according to the lengths of hits, means to field the ball, and electro-mechanical means controlled by the fielding means to put a runner figure out.

60. A ball game apparatus comprising a platform, a ball, means to move runner figures, means to bat or impel the ball, electro-mechanical means to move the runner figure moving means different distances according to the lengths of hits, means to field the ball, means to pitch the ball, and electro-mechanical means controlled by the fielding means to put a runner figure out.

61. A ball game apparatus comprising a platform, a ball, means to move runner figures, means to bat or impel the ball, means to move the runner figure moving means different distances according to the lengths

- of hits, means to field the ball, means controlled by the fielding means to put a runner out, and means to indicate balls, strikes and outs.
62. A ball game apparatus comprising a platform, a ball, means to move runner figures, means to bat or impel the ball, means to move the runner figure moving means different distances according to the lengths of hits, means to field the ball, means controlled by the fielding means to put a runner figure out, means to indicate balls, strikes and outs, and means to register balls, strikes and outs.
63. A ball game apparatus comprising a platform, a ball, means to move runner figures, means to bat or impel the ball, means to move the runner figure moving means different distances according to the lengths of hits, means to field the ball, means controlled by the fielding means to put a runner figure out, means to indicate balls, strikes and outs, and means to register balls, strikes and outs.
64. In an apparatus for playing the game of base-ball, the combination of a platform having a slot and turnouts at the bases in communication therewith, a sprocket belt movable below the platform, means for moving said belt, a runner figure movable in the slot and by the belt, and switch points under control of players for diverting a runner figure from the slot into the turnouts.

In testimony whereof we affix our signatures.

FREDERICK L. FOX.
FRANK C. GIBSON.
